UNITED STATES PATENT OFFICE.

GEORGE E. WITT, OF SAN FRANCISCO, CALIFORNIA.

LOCOMOTIVE OIL-BURNER.

No. 870,402.

Specification of Letters Patent.

Patented Nov. 5, 1907.

Application filed September 19, 1905. Serial No. 279,188.

To all whom it may concern:

Be it known that I, GEORGE E. WITT, a citizen of the United States, residing at San Francisco, in the county of San Francisco and State of California, have 5 invented certain new and useful Improvements in Locomotive Oil-Burners; and I do hereby declare the following to be a full, clear, and exact description of the same, such as will enable others skilled in the art to which it appertains to make and use the same.

10 This invention relates to improvements in oil burners, and more particularly to those used in locomotives, and it has for its objects to provide a device of this class which shall possess superior advantages in points of simplicity of construction, as well as inexpensiveness and general efficiency.

In my invention I have made it possible to regulate the size of the flame without the necessity of delicate and readily destructible mechanism.

15 In my present invention there are no adjustable parts liable to get out of order, as the burner proper is made of a single casting.

Other objects and advantages of the invention will appear in the following specifications, and the novel features thereof will be particularly pointed out in the 20 appended claims.

In the accompanying drawings, in which similar letters of reference designate corresponding parts:—Figure 1 is a longitudinal central section of the burner. Fig. 2 is a transverse section on the line xx of Fig. 1. 25 Fig. 3 is an end view of the mouth of the burner.

30 Referring now to the above views, A represents the main body of the burner which is a hollow casting with the central web B which divides the interior into the longitudinal passages C and D, the former for the passage of oil and the latter for steam. Leading to the rear of the upper passage C is the threaded boss E which is adapted to receive the oil pipe; while the passage D terminates in the threaded boss F which receives the steam pipe.

40 The forward end of the oil passage C is open; while that of the steam passage D is closed with the exception of a transverse horizontal slot (a). The end wall of the passage D, through which the slot (a) is cut, sets back slightly from the extremity of the main casting 45 thereby forming a lip (b) which inclines downward toward the center of the casting as shown in Fig. 3.

From the description so far gone into it will be readily seen that as the oil reaches the outer extremity of the passage C it will flow downward until it reaches the slot (a) when the steam issuing from the slot will intermingle with the oil and produce the desired result.

Now directly below the lowest portion of the lip (b)

is a hollow projection G into which is cut the slot (g). The small pipe H which is threaded into the projection G is provided to carry steam to the slot (g). Now it is manifest that when it is desired to reduce the flame the steam passing through the passage D is cut off and allowed to flow through the small pipe H. Of course the oil flowing into the lip (b) will overflow and finally 55 reach the small slot (g) where the diminished flow of steam is encountered and a correspondingly small flame is the result. It will be noticed by reference to Figs. 1 and 3 that the upper edges of the lip B dip slightly inward in order to prevent the oil from flowing from the lip until it reaches the lower portion thereof.

The rear leg J and central legs K are merely for the purpose of holding the small pipe H in place.

The construction and arrangement of the several 70 parts of my burner being thus made known, the operation and the many advantages of the same will, it is thought, be readily understood by those familiar with the use of oil burners.

Having thus fully described my invention, what I 75 claim and desire to secure by Letters Patent is:—

1. In a device of the character described, a hollow casing having a central web dividing its interior into parallel upper and lower passages, said casing having means by which said passages may be respectively connected to an oil and steam supply, said oil passage extending through the front end of the casing and said web terminating short of the front extremity of the casing, and said casing having a vertical wall connecting with the front end of the web and extending over and closing the front end of the 80 underlying steam passage except for a slit in said wall, said casing having a lip positioned in front of and below said slit, to enable the oil emerging from the oil passage to flow downward over said wall and across said slit into the range of action of the steam issuing from the latter. 90

2. In an oil burner the combination of a hollow casing having a web which divides its interior into upper and lower passages for oil and steam respectively said web terminating short of the front end of the casing and connecting with a vertical wall which extends across the front 95 end of the steam passage and closes said steam passage except for a slit formed in said wall, and a lip at the base of the vertical wall and projecting in front thereof below said slit, said casing having a hollow projection on the lower part of its front end and closed on all sides except 100 for a slit in its front wall below said lip, and a supplemental steam pipe entering said hollow projection and delivering steam thereto whereby oil overflowing the lip will flow down over the wall of the hollow projection and into the range of action of the steam delivered through the slit 105 in said projection.

3. An oil burner provided with oil and steam passages having outlets arranged in parallel relation, the oil outlet being provided with a gutter of maximum depth at the center and having a rear dam wall, a central bottom wall, 110 side walls inclining downwardly from the sides of the outlet to the bottom wall, and barrier lips projecting up-

wardly from the outer edges of the side walls in parallel relation to said dam wall and inclining downwardly from the sides of the outlet to said bottom wall, the bottom wall forming a shelf of restricted width between the lower ends of the side walls and barrier lips.

4. An oil burner provided with oil and steam passages having outlets arranged in parallel relation, the oil outlet being provided with a gutter of maximum depth at the center and having inclined side walls leading thereto, and

10 lips projecting upwardly from said side walls and inclined toward the deepest portion of the gutter and separated to form a shelf for the reduced flow of oil therethrough.

In testimony whereof, I have signed my name to this specification in the presence of two subscribing witnesses.

GEORGE E. WITT.
